DRAG REDUCTION SHROUD FOR JET ENGINES

Lorne C. Dunsworth, Van Nuys, and Arthur N. Thomas, Jr., Northridge, Calif., assignors to The Marquardt Corporation, Van Nuys, Calif., a corporation of California

Filed Feb. 3, 1958, Ser. No. 712,981

10 Claims. (Cl. 60—35.6)

This invention relates to a drag reduction shroud for jet engines and more particularly to a perforated shroud surrounding the nozzle of a jet engine to reduce drag and having openings therein to permit heat dissipation by radiation from the nozzle wall.

In high speed jet engines, such as ramjets and turbojets which are located in the air stream, it is customary to form the exit nozzle as an extension of the forward engine surface and to form the exit nozzle of thin sheet material similar to that forming the forward surface of the engine. When the complete engine is located in the airstream, the surface of the engine forward of the nozzle does not result in undue drag since the surface is substantially cylindrical. However, since the exit nozzle has a throat section and convergent and divergent sections, the nozzle surface presents a high drag contour to air flow past the engine. While the cylindrical surface of the engine could be extended to cover the exit nozzle, such an extended surface would not permit the required radiant heat dissipation from the nozzle to space in order to maintain the nozzle structure within the temperature limit. Therefore, no covering for the exit nozzle has been utilized.

By the present invention, the drag at the exit nozzle portion of the engine is reduced while permitting sufficient radiant heat dissipation from the nozzle. A perforated cylindrical shroud is extended from the forward cylindrical surface of the engine and surrounds the exit nozzle. The shroud contains a plurality of small openings, distributed over the complete shroud or over a selected area of the shroud. Since the axis of these openings are perpendicular to the direction of air flow past the engine, they do not substantially disturb the air flow past the shroud and thus, less drag results than when the nozzle surface is uncovered. Also, the openings are transparent to the flow of radiant energy from the nozzle to the air stream so that sufficient cooling of the nozzle is provided for. Obviously, the size and the number of holes in a unit area of the shroud will be selected to provide the required heat dissipation with minimum drag. Also, the percentage of open area provided by the holes can be greater in the portion surrounding the convergent section of the nozzle than in the portion surrounding the divergent section since the nozzle wall is subjected to higher temperatures at and forward of the throat section.

It is therefore an object of the present invention to provide a drag reduction shroud surrounding the nozzle of a jet engine and having a plurality of openings which are transparent to flow of radiant energy from the nozzle and opaque to air flow past the engine.

Another object of the invention is to provide a cylind-

2

rical shroud for the exit nozzle of a jet engine which reduces the drag of the engine while permitting sufficient heat dissipating from the nozzle.

A further object of the invention is to provide a shroud surrounding the exit nozzle of a jet engine and containing a plurality of openings transparent to radiant energy, the percentage of open area provided by said openings being greater in the forward portion of the shroud surrounding the portion of the nozzle subjected to highest temperature.

These and other objects of the invention not specifically set forth above will become readily apparent from the accompanying description and drawings in which:

Figure 1 is a side elevational view, partly in section, of the rear portion of a jet engine and showing the plurality of openings in the shroud which surrounds the exit nozzle.

Figure 2 is a vertical section along line 2—2 of Figure 1.

Figure 3 is an enlarged section taken along line 3—3 of Figure 2.

The embodiment of the invention chosen for illustration comprises a jet engine having a cylindrical section 5 located forward of the exit nozzle and supported by a strut 6 connected to the air frame or other structure propelled by the engine. The forward end 7 of convergent-divergent nozzle 8 is positioned within the aft end of section 5 and is attached thereto along weld line 9 in order to secure the nozzle to the engine. Nozzle 8 has a throat section 10, a convergent section 11 and a divergent section 12 and serves to produce thrust by discharging high temperature, high pressure gas or working fluid from the engine. A refractory coating 13 lines the interior of the cylindrical section 5 and of the nozzle in order to protect these components from the working fluid and reduce the temperature to which these components are subjected. A ring 14 surrounds the divergent section of nozzle 8 and is welded thereto to reinforce the nozzle structure.

A cylindrical ring 15 is partially inserted into the open end of cylindrical section 5 and is secured thereto along weld line 16. The portion of ring 15 extending aft of section 5 is received by one end of a perforated cylindrical shroud 17, which is secured to the ring by a plurality of bolts 18 spaced around the ring. The shroud 17 forms an extension of the cylindrical section 5 and completely surrounds the exit nozzle 8, thus forming space 19 between the shroud and the nozzle. Also, the aft end of the shroud extends slightly beyond the end of the nozzle.

Referring to Figures 1 and 3, the shroud 17 contains a plurality of circular openings 20 which have the same diameter and are arranged in circular rows around the shroud. The openings in each row and the rows themselves are spaced apart by the same amount and the openings in one row are staggered with respect to the openings in adjacent rows. In the area of the shroud designated A which surrounds the divergent and throat sections of the nozzles, the spacing between the openings and the rows results in approximately fifty percent open area in the shroud. However, in the area of the shroud designated B which surrounds the divergent section of the nozzle, the spacing between the openings and rows is greater so that the percentage of open area in area B of the shroud is considerably less than in area A. This difference in percentage open area provides for a greater

amount of radiant energy transfer through area A of the shroud, which surrounds the sections of the nozzle in which the gas temperature is the highest. Because of the lower gas temperature in the divergent sections 12 of the nozzle, the percentage open area in area B of the shroud can be reduced and still provide for sufficient transfer of radiant energy from the nozzle to the air stream.

During operation of the engine, hot gas or working fluid, represented by arrows C, flows through section 5 and through exit nozzle 8 to produce thrust and the air flow past the engine is represented by arrows D. Since the direction of air flow is parallel to the surface of the shroud and perpendicular to the axial line of the openings, the shroud is substantially opaque to the air flow. Also, there is no disturbance of the air flow at the junction of section 5 and shroud 17 since the shroud is in effect an extension of section 5. Thus, the drag on the engine is below that which would result if the irregular nozzle surface were presented to the air flow past the engine. However, the openings in the shroud are transparent to energy, represented by arrows E, radiated from the nozzle 8 so that heat can be dissipated from the nozzle to the air stream. Thus, the shroud 17 results in reduction of drag on the engine and at the same time, permits sufficient cooling of the nozzle.

The amount of drag reduction accomplished by the shroud will be determined by the size of the individual openings and by the percentage open area in the shroud resulting from the openings, and the amount of radiant energy passing through the shroud will be determined by the percentage open area. Thus, the opening size and percentage open area can be varied to obtain the desired balance between drag reduction and radiant energy transfer. For supersonic ramjet engines, it is preferable that the dimension of each individual opening in the flow direction not exceed one fourth of the boundary layer thickness and that the percentage open area in the shroud be varied by varying the number of the openings rather than the size of the openings. In general, the thickness of the boundary layer will increase with increase in the size of the engine and for a twenty-eight inch diameter engine, circular holes of quarter inch diameter have been utilized with satisfactory results. Also, it is preferable to distribute the openings uniformly in the shroud in order to uniformly cool the nozzle and prevent hot spots in the nozzle. It has been determined that with a fifty percent open area throughout the shroud, engine drag is reduced by about five percent at a flight speed of Mach 2.5. With the same shroud, specific fuel consumption is decreased about seven percent at maximum engine thrust and is reduced by about thirty percent at low cruising thrust. Substantial improvement in engine performance has been obtained throughout the range of thirty to sixty percent open area but, of course, the invention is not limited to this range. The density of the openings per unit area of the shroud can be uniform throughout the shroud or can vary over different portions of the shroud, as illustrated in Figure 1. Also, the shape of the individual openings can be other than circular and the openings can be arranged in various related patterns in the shroud. Further, the shroud can be secured to the engine or to the nozzle in any suitable manner. Various other modifications are contemplated by those skilled in the art without departing from the spirit and scope of the invention as hereinafter defined by the appended claims.

What is claimed is:

1. In a jet engine, a cylindrical engine section forming an exterior surface of said engine adjacent the air flow past the engine during movement of the engine, an exit nozzle secured to the rear end of said section, and a cylindrical shroud secured to the rear end of said section and surrounding said exit nozzle, said shroud containing a plurality of openings located directly opposite at least a portion of said nozzle and of such size as to be sub-

stantially opaque to air flow past said shroud while permitting direct flow of radiant energy from the exit nozzle to the air flow past said shroud.

2. In a jet engine as defined in claim 1 wherein said openings are distributed in said shroud to provide the largest percentage open area in the section of said shroud surrounding the portion of the nozzle of highest temperature.

3. In a jet engine, a cylindrical engine section positioned adjacent to the air flow past the engine during movement thereof, a convergent-divergent exit nozzle having its forward end inserted within the open aft end of said section, means for securing said forward end of said nozzle to said section, a mounting ring having a portion thereof inserted into said aft end of said section rearwardly of the forward end of said nozzle and having a portion extending beyond the aft end of said section, means for securing said inserted portion of said mounting ring to said section, a cylindrical shroud of substantially the same diameter as said engine section and completely surrounding said nozzle, said extending portion of said mounting ring being located within the forward end of said shroud, means for securing said forward end of said shroud to said extending portion, and a plurality of openings in said shroud located directly opposite the surface of said nozzle and of such size as to be substantially opaque to air flow past said shroud while being transparent to the direct flow of radiant energy from said exit nozzle, said openings being distributed throughout the surface of said shroud.

4. In a jet engine as defined in claim 3 wherein said openings are distributed in said shroud to provide a larger percentage open area opposite the converging and throat sections of said nozzle than opposite the diverging section of said nozzle.

5. In a jet engine supported within the air stream and having a straight body section forming a portion of the exterior surface of said engine an exit nozzle having its forward end connected with said body section, a shroud surrounding said exit nozzle and being of substantially the same size and shape as said body section, said shroud containing a plurality of openings located directly opposite of at least a portion of said exit nozzle and of such size as to be substantially opaque to air flow past said shroud while permitting direct flow of radiant energy from said exit nozzle.

6. In a jet engine as defined in claim 5 wherein said openings are distributed in said shroud to provide substantially fifty percent open area in at least one portion of said shroud.

7. In a jet engine as defined in claim 5 wherein said openings are distributed in said shroud to provide a percentage of open area in the range between thirty and sixty percent in at least a portion of said shroud.

8. In a jet engine having an exit nozzle extending from a body section, a shroud positioned around said nozzle to reduce engine drag, and a plurality of openings in said shroud and opposite at least a portion of said nozzle for providing passages for the direct flow of radiant energy from said exit nozzle, said openings being of such size and number as to be substantially opaque to air flow past said shroud while providing for sufficient flow of radiant energy to cool said nozzle.

9. In a jet engine located at least partially in the air stream of a movable craft, an engine section forming a portion of the exterior surface of said engine and located in said air stream, an exit nozzle secured to the rear end of said engine section, a shroud positioned around said exit nozzle for reducing the drag resulting from air flow past said exit nozzle, and a plurality of openings located in said shroud opposite at least a portion of said exit nozzle and providing a path for the direct flow of radiant energy from said exit nozzle to the air stream, said openings being of such size and number as to be substantially

opaque to air flow past said shroud while providing for sufficient flow of radiant energy to cool said nozzle.

10. In a jet engine as defined in claim 9, wherein said engine section is cylindrical in shape, said shroud being of the same cylindrical size as said engine section to present the same exterior contour to the airstream as presented by said engine section.
